UNITED STATES PATENT OFFICE.

MARSHALL F. ROBBINS, JR., OF BROCKTON, MASSACHUSETTS, ASSIGNOR TO WHEELER REFLECTOR COMPANY, OF BOSTON, MASSACHUSETTS, A CORPORATION OF MASSACHUSETTS.

REFLECTOR.

1,119,455.

Specification of Letters Patent.

Patented Dec. 1, 1914.

Application filed December 26, 1912. Serial No. 738,555.

To all whom it may concern:

Be it known that I, MARSHALL F. ROBBINS, Jr., a citizen of the United States, and a resident of Brockton, county of Plymouth, 5 State of Massachusetts (whose post-office address is 156 Pearl street, Boston, Massachusetts), have invented an Improvement in Reflectors, of which the following description, in connection with the accompanying drawings, is a specification, like characters on the drawings representing like parts.

This invention relates to reflectors, being more particularly intended to provide an improved form of connection between the 15 main body of an electric light reflector and the canopy or top which incloses and supports the lamp. While intended more particularly to overcome defects existing in out-of-door reflectors, such as are used for street 20 lighting, it may also be applied to reflectors used for interior lighting.

In reflectors of the type referred to it is desirable to have a close and tight joint between the canopy and the reflector to which 25 it is attached in order to prevent the entrance of moisture to the parts protected by the canopy. I have found that a screw-threaded joint between the canopy and the reflector accomplishes the desired result, 30 while affording the required support to the reflector itself.

In order to protect the reflector and canopy, when the latter are made of sheet metal or other material susceptible to the 35 action of rust, acids, moisture and the weather, it is customary to enamel the exterior surface of the reflector and canopy as well as such portions of the interior surface thereof as are apt to be reached by moisture 40 or other damaging elements. In this class of reflector, however, it is practically difficult to screw one enameled surface into or against another without cracking or injuring the enamel and, if cracked or injured, 45 the enamel becomes useless to protect the metal. In the illustrative embodiment of my invention, therefore, I have not only shown a construction of canopy and reflector which provides a screw-threaded joint 50 between two members, but have also shown such construction as permits the adjacent surfaces of the canopy and reflector to be enameled while at the same time preserving such enamel against injury when the parts 55 are screwed one to the other.

The invention will be best understood by reference to the following description when taken in connection with the accompanying illustration of one specific embodiment thereof, while its scope will be more particularly pointed out in the appended claims.

In the drawings: Figure 1 shows in side elevation a canopy with its attached depending reflector; and Fig. 2 shows on an enlarged scale a section taken through the 60 canopy and the contained lamp socket.

Referring to the drawings and to the embodiment of the invention therein shown, I have illustrated a lighting fixture comprising a reflector 1 adapted to reflect light from the lamp 2. The reflector may be of any suitable material, but is preferably, though not necessarily, of iron or other metal having its exposed surface enameled either by 70 japan, porcelain enamel or other similar or equivalent protective coating represented by the heavy line at 11. To the upper part of the reflector is fixedly secured a supporting ring 3 by which the reflector is attached to the canopy 4, the latter customarily being 75 suspended from a supporting arm (not shown). The ring 3 may be a part of the hood, but herein for convenience of manufacture it is made separate therefrom but rigidly attached thereto. Within the canopy 80 4 there is contained the porcelain lamp base 5 of a lamp holding socket 6 together with the usual lamp supporting parts and connections.

The canopy 4 is preferably, though not 90 necessarily, formed of iron or other metal with its exterior surface like that of the ring 3 and reflector 1 enameled by japanning, porcelain enamel or other protective coating represented at 12. In order to provide 95 a threaded joint between the canopy and the ring 3 the latter is provided with an upturned extension 7 which is exteriorly threaded to engage the canopy and the part carried thereby and properly to protect the 100 surface of the ring 3, the enameling 11 extending not only over the exterior, exposed portion, but over the upturned, threaded portion as well. To suitably protect the metal of the canopy the enameling 12 extends not only over the exterior surface, but over the interior surface as well. To provide against injury to the enameled surface of the neck or the canopy when the latter is 105 screwed into position, an intermediate 110

2
 threaded sleeve 8 is employed of some other and preferably some softer material. Herein I have formed a threaded sleeve 8 of copper and the same is fixedly secured to 5 and within the shell of the canopy by bead-
 ing the lower edge 9 over the flanged end 10 of the canopy. This provides a threaded lining of relatively soft material fixed in the canopy and adapted to be screwed down 10 over the threads of the neck 9 without injuring the enamel thereon.

When the canopy is screwed down upon its seat it is held in fixed position thereon by engagement of the threaded canopy 15 sleeve 9 with the threaded neck 7. In this position the enameled surface 11 of the neck 7 is protected from injury as is likewise the enameled surface 12 of the canopy. The sleeve 8 is preferably copper or zinc so as not 20 to be affected by moisture. Other arrangements might be provided for, but by means of the construction shown the sides of the canopy are left smooth and present a better appearance.

25 It will be observed that no screws or breaks are necessary in the enameled surface of the connecting parts and that no chemical action is possible between the screw-threaded members. Apart, however, 30 from the advantage of this construction in connection with members having enameled surfaces, the screw-threaded joint between the canopy and reflector provides a weather-
 proof joint against the entrance of moisture 35 to the wiring connections of the socket, holds the reflector in absolute rigidity on the canopy and permits the reflector to be easily removed for cleaning without disconnecting the wires.

40 While for purposes of illustration I have herein shown and described one specific

form of the invention, it is to be understood that the same is not limited to the details of construction or specific arrangement of parts, but that the same may be varied with- 45 in wide limits without departing from the spirit of the invention.

Claims.

1. A lighting fixture having a reflector provided with an enameled surface, a canopy having a contained lamp support, said canopy also having an enameled surface and a screw-threaded connection between the canopy and the reflector, said connection including a threaded sleeve between the enameled surface of the canopy and the reflector. 50

2. A lighting fixture having a reflector provided with an enameled surface, a canopy having a contained lamp support, 60 said canopy also having an enameled surface and a screw-threaded connection between the canopy and the reflector-carrying member, said connection including a metallic threaded sleeve between the enameled sur- 65 face of the canopy and the reflector.

3. A lighting fixture having a reflector provided with an upturned threaded neck having an enameled surface, a threaded metallic sleeve adapted to engage said surface and a canopy having an exteriorly and interiorly enameled surface within the open end of which said sleeve is fixedly secured, whereby said reflector may be attached to 70 said canopy. 75

In testimony whereof, I have signed my name to this specification, in the presence of two subscribing witnesses.

MARSHALL F. ROBBINS, JR.
